CANE OR UMBRELLA HANDLE.

No. 20,145.

Patented Sept. 9, 1890.

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,145, dated September 9, 1890.

Application filed July 31, 1890. Serial No. 360,572. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Cane, Umbrella, or Parasol Handles; and I do hereby declare the following to be a full, clear, and exact description of the invention, such as will enable others skilled in the art to which it pertains to make and use it, reference being had to the accompanying drawing, which forms part of this specification.

My invention relates to an improvement in designs for cane, umbrella, or parasol handles; and it consists in a novel shape and configuration of parts, whereby a pleasing and beautiful effect is produced, as will be more fully described hereinafter.

The accompanying photographic illustration represents my invention.

A represents the main portion of the han-

die, which is given practically an L shape, and upon which is the figure of a dragon D, having the outer end or tip of the handle grasped in its mouth. This dragon is provided with 25 claws, wings, and a tail, which is wound around the inner end of the handle, as shown. The body of the dragon is bent or curved so as to follow the shape of the handle, and it is represented as in the act of biting the handle, 30 as shown.

Having thus described my invention, I claim—

The design for a cane, umbrella, or parasol handle, substantially as herein shown and described. 35

In testimony whereof I affix my signature in presence of two witnesses.

ALBERT ROSENSTEIN.
